PNEUMATIC SAW

Walter Zielonka, Warren, Mass.

Application December 21, 1938, Serial No. 247,128

5 Claims. (Cl. 121—164)

My invention relates to saws which are portable or semi-portable and which may be carried from one location to another where they may be readily set up for operation. While the combination disclosed in my specification discloses a pneumatic motor and a saw operated thereby, it will be understood that any other tool may be just as well actuated by said motor and that no or only a slight modification would be required to effect that purpose.

Having briefly outlined the purpose of my invention, I shall now describe same in detail with reference to the accompanying drawings, in which:

15 Fig. 1 shows a side view of my saw including motor and equipment.

Fig. 2 shows a top view of my saw including motor and equipment.

20 Fig. 3 shows a sectional view of a detail of the construction shown in Figs. 1 and 2, taken on line 3—3 of Fig. 2.

Fig. 4 shows a vertical sectional view taken through the motor shown in Fig. 1 on line 4—4 of same.

25 Fig. 5 shows a longitudinal sectional view of the motor.

Fig. 6 shows a longitudinal sectional view of the motor with valves in a different position.

30 Fig. 7 shows a vertical sectional view taken on line 7—7 of Fig. 5.

Fig. 8 shows a vertical sectional view taken on line 8—8 of Fig. 5.

35 Fig. 9 shows a vertical sectional view taken on line 9—9 of Fig. 6, but with piston removed from the motor.

Fig. 10 shows an enlarged view of a ratchet arrangement being a part of the construction disclosed in Fig. 1.

40 Fig. 11 shows a fragmentary view disclosing the connection between a rocker arm and a valve shown in Fig. 5.

Similar numerals refer to similar parts throughout the several views.

In general, my invention is composed of a motor 10 and a saw 11 actuated by said motor, it being understood that some other tool may be substituted for the saw. The motor is operated by compressed air which may be delivered from a tank or any other reservoir, indicated by numeral 15, through a flexible hose 13 through valve 14 into the interior of the motor. Depending from the lower section of the motor is a pin 21 supporting a beam 25 controlled by cable 23 and serving to hold log 22 in position. No provision is made for the support of the motor is shown, but as to

this detail no particular construction is claimed and obviously such support may be used as may be best suitable for the purpose.

After this general description, I shall now describe my invention in detail, starting with the motor as shown in Fig. 5. The motor comprises a chamber 29 which may be cylindrical in shape, one side of the cylinder being closed by wall 45. The open end of the cylinder is provided with internal threads 38, by means of which said chamber 29 may be screwed upon what will be designated as valve block 31. Said valve block, which may also be cylindrical, is provided with longitudinal passages to accommodate valves 32 and 33. The valves are made in the shape of tubes closed at both sides but are provided with ports or openings. These openings are marked 34, 35 and 36 respectively in valve 32, and 31, 36 and 33 respectively in valve 33. Supported on a pin 41 in chamber 29 is a substantially triangular 10 rocker 40 provided at its base with forked arms 42 and 42, which embrace ends of valves 32 and 33 between parallel flanges on said ends, said flanges being marked 44 and 44a and 45 and 45a respectively. A detail showing one of these 15 forked arms is being shown in Fig. 11. The apex of said rocker 40 is hingedly attached to a member 46 remaining under the tension of a coiled spring 47, said spring being appropriately seated on the inside surface of wall 45. The purpose 20 of this spring arrangement is to impart to the rocker 40 a quick action in the reversal of its position on the pivot and to insure a steadiness 25 of the rocker in one or the other of its alternate positions.

Secured to the valve block 31 and threaded into it is a hollow cylinder 48, closed at the outside end by cap 49. Disposed within the cylinder is piston 50 adapted for a slidable reciprocal action therein, said piston being mounted on shaft 51. 40 Mounted within the cylinder on the inside wall of cap 49 is another rocker 54 pivotally supported on brackets 56, the body of said rocker being provided with an opening to accommodate shaft 51 and a rod 58, which extends from the end of valve 45 32 and passes through cap 49. Numerals 52 and 53 indicate packing for said shaft and for said rod respectively. It must be added that piston 50 is provided with an air-tight aperture 57 to provide for sliding passage of valve 32.

In order to complete the description of the motor 10, it will be necessary to point out that valve block 31 is provided with two outlets 58 and 59, these outlets being placed so that they are alternately in registry with ports 35 and 38 55

on valves 32 and 33 respectively. The outlets 58 and 59 lead to a common port 60 on the side of the block, as shown in Fig. 8.

Before describing other elements of my power saw, I shall now describe the operation of the motor. As stated before, the motor is designed to be operated by compressed air. Said air, conducted from tank 15 through hose 13 and through inlet 14a, enters chamber 29, as shown in Fig. 5. 5
10 From the chamber it enters inlet 37 of the lower valve 33 and is forced out at the other end of the valve through port 39 into the inside of the cylinder 48 into a space between piston 50 and valve block 31. Here it exerts pressure against piston 59, pushing said piston to the outer end 15 of the cylinder. Air which is contained in said cylinder on the opposite side of piston 50, that is within the space between piston 50 and cap 49, is forced out from said space through port 36 in 20 valve 32, and passing through the length of said valve comes out through outlet 35 when it is conducted through a conduit 58 in the valve block 31 to port 60. When, however, piston 50 reaches the outer end of cylinder 48, it is forced 25 against lug 54a of the rocker 54, whereupon the opposite arm 54b of said rocker swings inwardly into the cylinder and pushes valve 32 inwardly into the cylinder so that its opposite end, provided with flanges 44 and 44a, is projected into 30 the interior of chamber 29. When this occurs, rocker 40, pivoted on pin 41 and actuated by said valve 32, reverses its position and with the aid of spring 47 snaps valve 33 inwardly. The new position of the rocker and valves is shown in Fig. 6. 35 It will be seen that in this new position inlet 37 is closed by having been moved into the interior of block 31.

Compressed air, which continues coming into chamber 29, is now diverted into inlet 34 of valve 40 32 and is forced out at the other end of the valve through outlet 36. Released into the space between piston 57 and cap 49, it forces the piston inwardly in the direction of the valve block 31, while air contained on the other side of piston 50 is forced out through port 39 and escapes by 45 means of outlet 59 into the discharge port 60. Piston 50 continues to move so until it comes in contact with the end of valve 33 protruding into the inside of cylinder 48, whereupon said end is 50 pushed towards the block 31. As a result thereof, the opposite end of the valve is made to actuate the rocker 40, whereupon same snaps back into position shown in Fig. 5. When this occurs, inlet 37 is uncovered, inlet 34 is closed and the 55 action of the piston by means of the compressed air conducted into cylinder 48, is repeated as stated above.

Sometimes it may be necessary to adjust the position of valve 32, particularly before the motor is started, and this may be done manually by lever 51 pivoted on axle 62 and provided with a handle 63, said lever being suitably supported on the outside surface of cap 49.

It will be seen from the above description that 60 65 when compressed air is released into chamber 29, said air causes the piston to move back and forth in a reciprocal motion within the cylinder 48. This movement is utilized for the purpose of actuating any tool, and particularly a saw, which 70 by means of a suitable mounting may be attached to shaft 51 of said motor. This is shown in Figs. 1, 2 and 3 wherein 11 is a saw mounted in a T block 12, provided with a vertical slot 17 to accommodate same. The lateral ends of the T head of said block are provided with horizontally

disposed grooves 18. Affixed to the sides of the motor 10 by screws or bolts 76 are longitudinal plates 77 extending in parallel with the axis of the motor and beyond cap 49. These plates, which may best be made of cast metal, are provided on the inside surfaces thereof with projections or rails 19 and it is on these rails that block 12 is adapted to slide back and forth actuated by the reciprocal motion of piston 50 within cylinder 48. A sectional view of the T block and rails 19 projecting from said plates is shown in Fig. 3. 10 15

In order that saw 11 may be kept in operative contact with the object to be sawed, which in this case is indicated as a log 22, a special provision was made which will be described as follows:

Log 22 is held in position by claws 23 and 24, affixed to beam 25, said beam being pivotally and removably mounted by means of a yoke 20 on pin 20 21 supported in a bracket 26. The latter is placed below the valve block of the motor and is integrally connected therewith. Said beam is best made of two parallel planks held together by bolts or screws, as shown in the drawing. One 25 of the above mentioned claws 24 is movable and may be selectively placed by means of a pin to be inserted through transverse apertures 27 and 27a in beam 25. The arrangement further comprises a cable 28, one end of which is wound on 30 a drum 64; the other end of the cable is looped over pulley 65, passes over sheaves 66 and 67 and is attached to member 69.

It is by means of this cable, which gradually is wound up on drum 64 during the operation of the 35 saw, that said saw 11 is kept in operative contact with log 22. When, however, the saw cuts into the wood, this contact between the saw and the log may become loose. To overcome this loose contact, therefore, my invention comprises an arrangement whereby the cable may be tightened 40 gradually and progressively and this is accomplished by means of the ratchet arrangement shown in Fig. 10. Said ratchet arrangement comprises a double armed lever 70, pivoted on axle 71, 45 which also serves as the axle of the drum. Included in the construction is also a ratchet wheel 72 controlled by a driving pawl 73 and a checking pawl 74. The lever 70 is provided with arm 75 extending upward and adapted to be raised by 50 T block 17 every time that the saw progresses in the direction of the motor 10. When this is done, that is when said block 17 raises arm 75, the driving pawl 73 imparts a rotary motion to wheel 72 and to drum 64 and the slack of the cable is taken up by said drum. It will be seen, therefore, that as the saw cuts deeper into the log, the 55 cable is progressively wound up on the drum and the saw is kept in close contact with the log being cut. There is a possibility, however, that sometimes the drum might rotate faster than would be justified by the cutting action of the saw. If such were the case, the work of the saw would be impeded by excessive friction and the saw would bear too heavily against the material to 60 be cut. It was for the purpose of obviating this possibility that a coiled spring 68 was employed by me in this construction. It will be seen that this coiled spring 68 is supported by a bracket 76 and that said spring bears against the lower 70 surface of member 69. When owing to the slow action of the saw the cable is tightened more than ordinarily would be desirable, the cable exerts excessive pull upon member 69 and this pull, being greater than the resistance of spring 75

68, causes said spring to yield, whereupon the whole lever 70 is tipped to one side, raising arm 75 so that it cannot be actuated by block 17 until the saw had time to bite deeper into log 22. Then, 5 upon slackening of the cable, the tension of the spring will allow lever 70 to come back to its normal position so that arm 75 might be again actuated by the shoulder 17 of the saw.

It will be obvious that some changes in the 10 construction and combination of parts shown herein are possible and that such changes may be made without departing from the principal idea disclosed herein. What I, therefore, wish to claim is as follows:

15 1. A motor to be operated by compressed air, comprising a cylinder, a piston disposed therein, an air chamber, a valve block between said cylinder and said chamber, tubular valves slidably disposed in said valve block and adapted to conduct compressed air into said cylinder, and means responsive to the action of the piston to direct compressed air from said chamber by means of said valves into the cylinder alternately into the 20 space on one side or the other side of said piston, 25 to effect a reciprocating movement of said piston.

2. A pneumatic motor comprising a cylinder, an airtight piston therein, a chamber outside said cylinder, tubular slidable valves connecting said air chamber with the cylinder, provided with inlets and outlets, each valve in turn being adapted to conduct air into the cylinder to one side of the piston while the other is adapted to release air from the opposite side of said piston, the function of said tubes changing alternately in response to means actuated by the motion of the piston.

3. A motor adapted to be operated by compressed air, comprising a cylinder, a piston slidably disposed therein, an air chamber disposed at 30 one end of said cylinder, slidable tubular valves disposed in a valve block placed between the cyl-

inder and the air chamber, each valve being provided with an inlet to receive air from the air chamber, a port at the opposite end of the valve to release air into the cylinder, an intermediate port to release air from said cylinder and means 5 operated by a piston to control the movement of the slide valves to direct compressed air into the cylinder to one side of the piston, while air on the other side of said piston is released through the other valve, the function of the valves being 10 alternated by said means.

4. A motor comprising a closed cylinder, a piston adapted to move therein, in a reciprocating motion, a chamber at one end of the said cylinder, a valve block between the air chamber of the cylinder, tubular valves slidably disposed in said valve block, one of said valves extending through the movable piston substantially to the further end of the cylinder, each valve being provided with an inlet from the air chamber, a port at its other end and an intermediate outlet within the confines of the valve block, rocker means actuated by the action of the piston to slide the valves alternately into the chamber, to alternately convey compressed air into the cylinder to one side 20 of the piston, while the air on the other side is released through the other valve through said intermediate outlet therein.

5. A motor comprising a cylinder, a piston adapted to be actuated therein by compressed air, 30 an air chamber at one end of said cylinder, a tubular valve to convey air from the air chamber into the cylinder to one side of said piston, a valve to convey air from said air chamber to the other side of said piston, rocker means within the air chamber actuated by the action of the piston to alternately admit air into the valve from the air chamber, said valves acting alternately to release spent air from the cylinder.

35

WALTER ZIELONKA.
